UNITED STATES PATENT OFFICE.

EDWARD BRETCH, OF ST. LOUIS, MISSOURI.

ALTERNATING-CURRENT MOTOR.

No. 848,719.

Specification of Letters Patent.

Patented April 2, 1907.

Application filed November 17, 1905. Serial No. 287,803.

To all whom it may concern:

Be it known that I, EDWARD BRETCH, a citizen of the United States, residing at St. Louis, Missouri, have invented a certain new and useful Improvement in Alternating-Current Motors, of which the following is a full, clear, and exact description, such as will enable others skilled in the art to which it appertains to make and use the same, reference being had to the accompanying drawings, forming part of this specification, in which—

Figure 1 is an end view, partly broken away, of a motor embodying the features of my invention. Fig. 2 is a longitudinal sectional view of the motor shown in Fig. 1. Fig. 3 is a detail view of one of the sections of the field-core and one of the sections of the armature-core. Figs. 4, 5, and 6 illustrate my improved armature used in motors having, respectively, a series connection, a repulsion or induction connection, and a three-phase circuit; and Fig. 7 is a detail view showing a modified form of my invention.

This invention relates to dynamo-electric machines for use on electric circuits wherein the current alternates, and particularly to the armatures used in such machines.

The object of my invention is to provide a machine in which the armature is of very simple construction and when employed in motors can be started under load without the use of complicated mechanism and with a minimum starting-current.

Another object is to provide a novel armature which will eliminate sparking at the commutator without the use of power-consuming resistances, divided windings, and similar devices which it has been necessary heretofore to use for this purpose.

Other desired features of my invention will be hereinafter pointed out.

I have shown the preferred form of my invention as embodied in an armature provided with two low-resistance windings separate and distinct from each other. Preferably said armature is used in combination with a laminated field-core having a number of polar projections, which may be wound in any well-known manner common to alternating-current machines, one winding of the armature being preferably connected to a commutator cooperating with brushes. The connections between the armature and field may be in any of the well-known ways, or, if desired, the brushes may be short-circuited.

In the embodiment of my invention herein shown the armature is made up of a plurality of slotted laminations of magnetic material, and the slots in said sections receive an outer winding, which is similar and is connected to the commutator as in direct-current armatures, and an inner winding of the squirrel-cage type of low resistance embedded in said core and separated some distance from the outer winding.

Referring to the drawings, which represent a device embodying the preferred form of my invention, 2 designates a frame having revolvably mounted therein an armature-shaft 4, carrying an armature-core 6 and a commutator 8, connected to a winding on the armature. A field-core 10 is mounted in a frame surrounding the armature, and the commutator cooperates with pivotally-mounted brushes 12. As shown in the drawings, the field-core is composed of a plurality of slotted laminations of magnetic material provided with a winding of well-known type. One of the slotted laminations of the armature is shown in detail in Fig. 3. Extending transversely through openings in the laminations comprising the armature-core are a plurality of bars 16 of low resistance, preferably of copper or brass, and connected to the opposite ends of said bars are disks or plates 18, formed of copper or brass and constituting a squirrel-cage inner winding separated some distance from the outer winding to form a path for the magnetic flux between the two windings. These bars, as here shown, are circular in cross-section; but in many cases it is advisable to use bars of oblong or rectangular cross-section in radial slots to provide a maximum cross-section of conductor in the squirrel-cage with the least reduction of the cross-section of the magnetic core.

In Fig. 4 I have shown my novel form of armature as embodied in a motor having a series connection, in Fig. 5 having a repulsion or induction connection, and in Fig. 6 as connected for a three-phase circuit. In a similar manner a connection can be made for a two-phase circuit. The best torque characteristic for starting heavy loads is that of the series direct-current motor. Polyphase induction-motors with short-circuited armatures do not possess this characteristic; but for some classes of work their torque characteristic has proved satisfactory. Single-phase motors of this type have no starting torque at all unless provided with some

phase-splitting device, and then it is small and the starting-current exceedingly large, and to start heavy loads automatic clutch-pulleys which throw the load on the motor 5 after it has attained its speed must be used. This is generally accomplished by some device either manually or centrifugally operated to disconnect the phase-splitting device at running speed. These devices besides being 10 expensive are a great source of trouble and are likely to burn out if for any reason the motor cannot start promptly. Another method which utilizes the series starting characteristic employs a commutator on the 15 armature, but owing to the destructive sparking must be short-circuited and cut out of service except for starting, which may be done either manually or centrifugally. While this gives a better starting characteristic, it 20 is expensive and very likely to get out of adjustment.

A motor as shown diagrammatically in Figs. 4, 5, or 6 will have the series starting characteristic and short-circuited armature 25 induction-motor-running characteristic—namely, constant speed under varying loads. As previously pointed out, a motor having the series characteristic above referred to had to be provided with expensive and complicated centrifugal devices to short-circuit the armature at the proper speed. My novel armature accomplishes the same result without the use of such devices, as at standstill or slow speed the magnetic flux in the armature, 30 due to its high rate of alternations, will be forced outside the squirrel-cage winding in the path between said winding and the outer winding, so that the squirrel-cage winding will be inoperative. At or near synchronous 35 speed, however, the magnetic flux, due to its low rate of alternations in the armature, will penetrate the squirrel-cage winding, and thus cause it to become operative automatically, thereby producing the characteristics of a 40 short-circuited winding. Furthermore, the speed at which the short-circuited characteristic manifests itself depends on the "slip" 45 and not on the absolute speed, as in centrifugally-controlled devices, so that a wide range 50 of alternations in the supply-circuit is permitted. In a motor employing a centrifugal device said device must be carefully adjusted and the "frequency" of the circuit held close to that for which it is adjusted or it will fail. 55 In my armature the squirrel-cage winding not only eliminates sparking and gives the short-circuited characteristic at running speed, but also makes the armature more effective, so that heavier loads can be carried, 60 allows the short-circuited characteristic to manifest itself at the proper speed irrespective of the absolute speed, and to come on gradually, so that any shock or disturbance on the line is avoided.

65 Another advantage of my invention is that

the speed of the motor can be controlled by a suitable resistance or the starting-current held down to full-load current in the same manner as in a direct-current motor. Alternating-current motors with short-circuited 70 armatures are not satisfactory as variable-speed motors, and on single-phase current they will not operate except near synchronous speed. By the use of my armature single-phase motors may be operated at any 75 speed below synchronous speed by connecting a suitable rheostat in series with the motor or by shifting the brushes and varying the relation between the windings they can be operated at speeds above synchronism 80 when it is desirable.

By connecting the armature and field in series and with the proper windings on the field and armature the power factor may be made very much higher than with the short-circuited armature; but for motors of small size in order to secure the greatest simplicity I prefer to short-circuit the brushes and run as a repulsion-motor. In this manner only low voltages are applied to the revolving armature, making insulation extremely simple, and an armature will work equally well in fields wound for different voltages. This arrangement is also a great improvement over an armature having some short-circuited 95 coils in the slots with the armature-winding. Such coils are usually of high resistance to prevent them from burning out at slow speed, in which case they are of little advantage at running speed. If these coils are of low resistance, the starting-current becomes excessive and the starting torque reduced. Either arrangement is open to the same objection as phase-splitting devices—that if the motor 100 cannot start promptly the coils will burn out. Placing a squirrel-cage winding on the surface of the armature-core in connection with the commutated winding while not so liable to burn out gives no better results. 105

Having thus described my invention, what 110 I claim as new, and desire to secure by Letters Patent, is—

1. In a dynamo-electric machine, a magnetic field in combination with an armature having a core of magnetic material, an outer winding carried by said core, means for controlling and directing the flow of the current in said winding, an inner winding located within the zone of the outer winding and separated therefrom to form a pathway for 115 the magnetic flux to pass through the outer winding without penetrating the inner winding; substantially as described.

2. An armature comprising a core of magnetic material, a commutated winding of low 125 resistance located at the periphery of said core, an inner winding of low resistance located within the zone of the commutated winding and separated therefrom to form a pathway for the magnetic flux to pass through 130

the commutated winding without penetrating the inner winding; substantially as described.

3. An armature comprising a core of magnetic material, a commutated winding of low resistance located near the periphery of said core, a squirrel-cage winding embedded in the core within the zone of the commutated winding and separated therefrom to form a pathway for the magnetic flux to pass through the commutated winding without penetrating the squirrel-cage winding; substantially as described.

4. An armature having a slotted laminated core of magnetic material, a commutated winding carried by the slotted portion of said core, an inner winding consisting of transversely-extending bars of conducting material embedded in the core within the zone of the commutated winding and separated therefrom to form a pathway for magnetic flux to pass through the commutated wind-

ing without penetrating the inner winding, and conducting means connected to the ends of said bars; substantially as described.

5. In a dynamo-electric machine, a slotted laminated field-core in combination with an armature having a core of magnetic material, a commutated winding of low resistance carried by said core, an inner winding of low resistance carried by said core and located within the zone of the commutated winding and separated therefrom to form a pathway for the magnetic flux to pass through the commutated winding without penetrating the inner winding; substantially as described.

In testimony whereof I hereunto affix my signature, in the presence of two witnesses, this 7th day of November, 1905.

EDWARD BRETCH.
